UNITED STATES PATENT OFFICE.

WILLIAM M. CRANE, OF NEW YORK, N. Y., ASSIGNOR TO WILLIAM M. CRANE COMPANY, A CORPORATION OF NEW YORK.

DESIGN FOR A GAS-RANGE.

No. 40,058.

Specification for Design.

Patented June 15, 1909.

Application filed April 23, 1909. Serial No. 491,870. Term of patent 7 years.

To all whom it may concern:

Be it known that I, WILLIAM M. CRANE, a citizen of the United States, and a resident of the city, county, and State of New York, have invented a new, original, and ornamental Design for Gas-Ranges, of which the following is a specification, reference being had to the accompanying drawing, forming part thereof.

The figure of the drawing is a perspective view of a gas range, showing my new design I claim:

The ornamental design for a gas range, as shown.

WILLIAM M. CRANE.
